UNITED STATES PATENT OFFICE.

JOHN R. MITCHELL, OF CHICAGO, ILLINOIS, ASSIGNOR TO W. H. MINER COMPANY, OF CHICAGO, ILLINOIS, A CORPORATION OF ILLINOIS.

TANDEM-SPRING DRAFT-RIGGING FOR RAILWAY-CARS.

SPECIFICATION forming part of Letters Patent No. 783,379, dated February 21, 1905.

Application filed September 28, 1904. Serial No. 226,270.

To all whom it may concern:

Be it known that I, JOHN R. MITCHELL, a citizen of the United States, residing in Chicago, in the county of Cook and State of Illinois, have invented a new and useful Improvement 5 in Tandem-Spring Draft-Rigging for Railway-Cars, of which the following is a specification.

My invention relates to improvements in 10 tandem-spring draft-rigging for railway-cars.

The object of my invention is to provide a tandem-spring draft-rigging of a strong, simple, efficient, and durable construction.

My invention consists in a tandem-spring 15 draft-rigging comprising, in connection with the draw-bar of the coupler and draw-bar strap, yoke, or extension, tandem-springs and followers, a pair of side plates or stop-castings having stops or shoulders for the followers to abut against, and upper integral guides, and provided with short feet, lugs or projections on their lower edges or faces, and lower removable guides furnished with integral tie-plates extending between the removable 20 guides and underneath the draw-bar strap or yoke and furnished with recesses to receive the short feet, lugs or projections on the lower faces or edges of the side plates or stop-castings.

My invention also consists in the novel construction of parts and devices and in the novel combinations of parts and devices herein shown or described.

In the accompanying drawings, forming a 35 part of this specification, Figure 1 is a side elevation, partly in vertical longitudinal section, of a tandem-spring draft-rigging embodying my invention. Fig. 2 is a plan view, partly in horizontal section. Fig. 3 is a cross-section on line 3 3 of Fig. 2, the section-line being also indicated on Fig. 4. Fig. 4 is a detail elevation of one of the side plates or stop-castings, showing one of the integral tie-plate members of the lower removable guides in cross-section. Fig. 5 is a detail top or plan view of one of the lower removable combined guides and tie-plates; and Fig. 6 is a detail cross-section on line 6 6 of Fig. 4, showing a slight modification.

In the drawings, A A represent the center 50 sills of the car; A¹, draft-timbers; A², the front or cross-sill; A³, the buffer-block; A⁴, the buffer-plate, and A⁵ the carry-iron.

B is the coupler; B¹, the draw-bar; B², the draw-bar extension, the same being preferably in the form of a yoke or strap secured 55 to the draw-bar by bolts or rivets b.

B³ is the abutment-block, which engages the middle followers and is secured to the strap or yoke B² by bolts or rivets b'. 60

C C' C² C³ are the followers, and E E' tandem-arranged springs.

D D are the side plates or stop-castings, each being furnished with integral stops or shoulders d d' d² for the followers to abut 65 against and each provided with an upper integral flange or guide d³, under which the followers reciprocate. Each of the side plates or stop-castings D is also provided on its lower edge or face with integral inwardly-projecting feet d⁴, which project downwardly beyond the lower face of the side plate or stop-casting and fit in shouldered recesses f in the lower removable combined guide and tie-plates F, which are preferably made of malleable 70 iron or other cast metal and two in number. The lower removable combined guide and tie-plate F has guide arms or members f', which extend longitudinally of the side plates or stop-castings and guide and support the followers at the ends thereof, and an integral cross or tie member f², uniting the members f' and extending underneath the lower limb or member of the draw-bar strap or yoke B². The removable combined guide and tie-plates 75 F are also furnished with upright flanges f³, which engage and embrace the side plates or stop-castings and serve to relieve the bolts f⁴ from shearing strain. The removable combined guide and tie-plates F are secured to 80 the side plates or stop-castings D D by short bolts f⁴, which extend through the inwardly and downwardly projecting feet or lugs d⁴ on the side plates or stop-castings D.

In the form of my invention illustrated in 95 Figs. 1, 2, 3, 4, and 5 the cross or tie member f² of the castings F supports the draw-bar strap or yoke B² and through the yoke guides

it in its longitudinal reciprocation, and the strap or yoke itself supports the followers. In the form illustrated in Fig. 6 the followers rest and reciprocate upon the guide members 5 $f' f'$ of the castings F , and the draw strap or yoke rests upon the followers.

I claim—

1. In a tandem-spring draft-rigging, the combination with the draw-bar and draw-bar strap or yoke, of tandem springs and followers, a pair of side plates or stop-castings having stops for the followers to abut against, and upper integral guides, and provided with projecting feet or lugs on their lower edges 10 or faces, and lower removable combined guides and tie-plates furnished with recesses to receive said feet or lugs on the side plates or stop-castings, said combined removable guides and tie-plates having upright flanges 15

engaging and embracing the side plates or stop-castings, substantially as specified.

2. In a draft-rigging, the combination with the draw-bar, draw-bar strap or yoke, spring and followers, of a pair of side plates or stop-castings having stops for the followers to abut 20 against, and upper integral guides, and provided with projecting feet or lugs at their lower edges or faces, and a combined lower removable guide and tie-plate secured to the stop-castings, said combined integral guide 25 and tie-plate having upright flanges engaging and embracing the stop-castings, substantially as specified.

JOHN R. MITCHELL.
